UNITED STATES PATENT OFFICE.

HENRY D. SMITH, OF EAST ST. LOUIS, ILLINOIS.

SYSTEM FOR LUBRICATING INTERNAL-COMBUSTION ENGINES.

Application filed May 1, 1923. Serial No. 335,889.

To all whom it may concern:

Be it known that I, HENRY D. SMITH, a citizen of the United States, residing at East St. Louis, in the county of St. Clair and State of Illinois, have invented certain new and useful Improvements in Systems for Lubricating Internal-Combustion Engines, of which the following is a specification.

10 Primarily this invention relates to means for supplying lubricating or heavy oil to the interiors of cylinders of an internal combustion engine and it consists in the novel features hereinafter described and claimed.

15 Coincidentally the invention serves as means for retaining and utilizing escaping gases within the explosion chambers of the engine and furthermore serves as means for subjecting the spark points of the ignition

20 devices to baths of heavy oil whereby carbon is prevented from accumulating upon the points.

The invention is intended to be applied to internal combustion engines such as are employed in the operation of motor vehicles and provides means for establishing a transportation system, extraordinary, for oil, from the crank case of the engine to the cylinders and applied to the inaccessible and more remote parts of the cylinders and pistons, effecting superior lubrication and economy by sealing, with heavy oil, the spaces around the peripheries of the piston rings and preventing the escape of the elements of gasoline from the cylinders and its delivery to the crank casing whereby the explosive elements are retained where they may be immediately utilized by the next succeeding explosion within the cylinders.

35 Various types of oiling systems are in use in different types of motors but in common, each has its reservoir from which oil is splashed or otherwise served to the moving parts, and it is notable that much vapor, containing gasoline, passes, under pressure, from the cylinders around the piston rings and thus gasoline finds its way and is delivered to the crank casing, where it cuts the oil and destroys its lubricating qualities. In the use of the present invention such destructive processes is prevented by sealing the spaces between the pistons and cylinder walls and confining the gases in the explosion chambers for use there.

40 A further object of the present invention

is to provide means for moistening and oiling the points of the electric devices which furnish the sparks to set off the mixture in the cylinders, so as to prevent the accumulation of carbon thereon and thereby inviting strong or hot sparks. This object is attained partly by serving heated oil and partly by the presence of steam within the cylinders. The steam is generated in the heater of the device by the separation of the water, usually present in small quantities in fuel oil, and its vaporization under the heating effects of the hot oil.

In the accompanying drawings—

Figure 1 is a side elevation of the device applied.

Figure 2 is a longitudinal sectional view of the same.

The other figures are detailed views of the features of the invention.

The device comprises a cup 1 adapted to be inserted in the mouth of the spout 2 of the crank casing 3 of the engine. A fitting 4 is inserted in the upper end of the cup and a breather nozzle 5 is fitted in the upper end of the fitting. A concaved pan 6 of thin metal is interposed between the lower end of the fitting 4 and the cup and the said pan is provided with openings 7 located near its edge. The fitting 4 is provided at its side with a nipple 8 to which one end of a hose section 9 is connected. A wick 10 extends through the hose section 9 and one portion of the wick is diametrically expanded as at 11 and the said expanded portion rests in the concavity of the pan 6. The breather nozzle 5 is provided with a rotatable cap 12 having a slot 13 which may be brought into register with a similar slot in the nozzle. This arrangement forms one of the air sets of the device. By turning the cap 12 the volume of the air which passes through the breather nozzle may be regulated and when the slots are completely out of register with each other the flow of air is stopped and the breather is made air tight. The oil or vapor of the oil in the crank casing may pass through the spout 2, cup 1 and the openings 7 in the pan and is absorbed by the expanded end 11 of the wick and by capillary attraction is carried by the wick through the hose section 9.

The heater of the device comprises a casting 15 of iron which is cored out and which is adapted to fit against the exhaust mani-

fold 16 of the engine. The heater casting is held in position upon the said manifold by a metal tape 17. The forward end of the casting is partially closed by a cap 18 which is turnably mounted upon the casting. The cap is provided with an opening 18 or openings, adapted to register with similar openings 19 in the sides of the casting and by this means the quantity of the air which is drawn through the casting is regulated. This device is the second air set.

The cap 18 is held at a set or adjusted position by a set screw 20 which engages the casting and which passes through a slot 21 in the side of the cap. The posterior end portion of the casting 15 is offset as at 22 and the end of the wick 10 terminates in this offset portion. This offset portion serves as a mixing chamber and may receive heated air from the body of the heater casting and oil vapor from the wick and hose section 9. By adjusting the air sets the relative quantities of the heated air and the vapor may be regulated.

To more thoroughly mix and split the currents entering the heater and mixing chamber, a fan 23 is freely journaled in the offset and is rotated by the currents passing therethrough. A hose section 24 connects the offset 22 with the carbureter 25 and in turn the carbureter is connected with the engine intake manifold 26 in a usual manner. The fan acts to agitate the combined currents from the offset to and through the connected hose 24 and the carbureter, where the said combined currents are mixed with the liquid fuel in the carbureter and is passed through the intake manifold into the upper portions of the engine cylinders.

By closing the air sets the oil vapor, if required, may be drawn from the crank casing to the heater by the suction created within the parts connecting the heater with the breather of the crank casing. By adjusting the air sets, oil vapor may be carried to the heater. The pan economizes the oil as the expanded end of the wick lies over the openings in the pan and the oil is compelled to filter through the fibre of the wick to pass above the pan. At the heater the oil undergoes a physical and chemical change as it is converted by heat

to refined oil and in a measure combining heated air producing steam.

Having described the invention what is claimed is—

1. Means for supplying lubricating oil to the interiors of cylinders of an internal combustion engine comprising a hose connected with the crank casing and the intake manifold of the engine, a heater connected in the hose and adapted to be applied to the exhaust manifold of the engine and means for inducting atmospheric air into the heater.

2. Means for supplying lubricating oil to the interiors of cylinders of an internal combustion engine comprising a hose connected with the crank casing and the intake manifold of the engine, a heater connected in the hose and adapted to be applied to the exhaust manifold of the engine, means for inducting atmospheric air into the heater and means for regulating the volume of air admitted to the heater.

3. Means for supplying lubricating oil to the interiors of cylinders of an internal combustion engine comprising a hose connected with the crank casing and the intake manifold of the engine, a heater connected in the hose and adapted to be applied to the exhaust manifold of the engine and a mixer located in the heater.

4. Means for supplying lubricating oil to the interiors of cylinders of an internal combustion engine comprising a hose connected with the crank casing and the intake manifold of the engine, means for inducting atmospheric air into the interior of the hose and a wick located in the hose and leading from the point of connection with the crank casing to the point of induction of the air.

5. Means for supplying lubricating oil to the interiors of cylinders of an internal combustion engine comprising a hose connected with the crank casing and the intake manifold of the engine, a pan located in the connection between the hose and the crank casing, a wick extending from the pan into the intermediate portion of the hose and means for inducting atmospheric air into the interior of the hose.

In testimony whereof I affix my signature.

HENRY D. SMITH.
